The ornamental design for an ultrasonic liquid level sensor and switch, as shown and described.

DESCRIPTION

FIG. 1 is a front bottom isometric view of an ultrasonic liquid level sensor and switch, showing our design;

FIG. 2 is a front view thereof;

FIG. 3 is a rear view thereof;

FIG. 4 is a right side view thereof;

FIG. 5 is a left side thereof;

FIG. 6 is a bottom view thereof; and,

FIG. 7 is a top view thereof.

The broken line showing in the drawings shows portions of the ultrasonic liquid level sensor and switch and forms no part of the claimed design.
